UNITED STATES PATENT OFFICE.

EUGENE KIBELB AND WALTER G. VREELAND, OF CHATTANOOGA, TENNESSEE.

PIPE-WRENCH.

1,118,937.

Specification of Letters Patent.

Patented Dec. 1, 1914.

Application filed December 4, 1913. Serial No. 804,738.

To all whom it may concern:

Be it known that we, EUGENE KIBELB and WALTER G. VREELAND, citizens of the United States, residing at Chattanooga, in the county of Hamilton and State of Tennessee, have invented certain new and useful Improvements in Pipe-Wrenches; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to a device for screwing and unscrewing pipe or casing and has for its object simple and effective means for screwing or unscrewing said pipe or casing, giving either a right or left hand rotation to the pipe without removing said wrench from the pipe or casing or changing the position of said wrench with reference thereto.

In the accompanying drawing, Figure 1 shows a plan or top view of the wrench, and Fig. 2 shows a side elevation of said wrench.

In Figs. 1 and 2, *a* is the handle of the wrench and *b*, *b* are cheeks or side plates of the wrench. *c* is one of the jaws of said wrench and *d* is another jaw of the wrench; *e* is a pivot upon which jaw *c* is mounted and through which it is connected to the cheeks or side plates *b*, *b* of the wrench. *f* is the pivot by means of which jaw *d* is connected to the jaw *c* and about which jaw *d* revolves. *h* is a movable bearing pin that may be placed either in a hole *g* in jaw *d* or in hole *j* of jaw *d*. *k*, *k*¹ are slots in the side plates or cheeks *b*, *b* through which the pin *h* may pass and with the walls of which the pin has a sliding or moving contact. *l* is a stop or tongue upon jaw *c* to limit its motion in one direction with reference to the handle *a*. *m* is a stop on handle *a* provided to limit the motion of jaw *c* with respect thereto. *n* is a stop provided on side plates or cheeks *b*, *b* to limit the movement of jaw *c* with respect thereto, and *o* is a stop provided on jaw *c* to limit its movement with respect to side plates *b*, *b*. *p*, *p*, *p* are removable teeth which may be either inserted into the portion of jaw *d* or may be attached thereto by any suitable means for

the purpose of providing a positive grip upon the pipe or casing upon which the wrench is used. *r*, *r* are bolts securing side plates or cheeks *b*, *b* to handle *a*. *s* is a chain or other means provided for securing the loose pin *h* to the wrench so that it may not be lost when removing from one of the holes in the jaw *d*.

While the drawing shows the preferred embodiment, the invention is not limited to such form, and the side plates or cheeks *b*, *b* may be made solid with the handle *a* thus making one continuous piece if so desired.

If it is so preferred the slots *k*, *k*¹ may be made one continuous slot, or the holes *h* and *j* may be placed in the side plates *b*, *b* and the slots *k*, *k*¹, or one continuous slot in their place, be provided in the jaw *d*, which would be a mere transposition of parts and embracing the invention.

Having described the parts of the wrench and designated them by the reference letters given above, the following is its operation: The wrench is applied to the pipe or casing by removing the pin *h* and swinging the jaw *d* about its fulcrum *f* permitting the wrench to be placed upon the pipe, after which the jaw *d* is closed and the pin *h* is inserted either in hole *g* or hole *j*, depending upon which rotation is desired. If a right hand movement of the wrench is desired, that is a movement in the direction of the hands of a clock, when looking upon the wrench as shown in Fig. 1, the pin *h* is placed in the hole *g*, passing through the slots *k*, in the side plates or cheeks *b*, *b*. The pin *h* passing through the hole *g* engages in the slots in both plates *b*, *b*. A movement of the handle *a* in a clockwise direction will then cause the jaws *c* and *d* to close upon each other and grip the pipe in such a manner that the teeth *p*, *p*, *p* will be brought into contact with its wall and rotate it in unison with the wrench. The greater the resistance offered by the pipe against rotation the greater will be the gripping action of the wrench jaws by reason of the leverage imposed by the short leverage or distance between the bolt *e* and the pin *h*. If a left hand rotation of the pipe is desired, that is a counter-clockwise direction, the pin *h* is removed and placed in the hole *j*, passing through the slots *k*¹ in both the plates or cheeks *b*, *b*. A movement of the handle *a* in a counter-clockwise direction will then

cause the jaws *c* and *d* to open and grip the pipe in such a manner that the teeth *p*, *p*, *p* will be brought into contact with its wall and rotate it in unison with the wrench. The greater the resistance offered by the pipe against rotation the greater will be the gripping action of the wrench jaws by reason of the leverage imposed by the short leverage or distance between the bolt *e* and the pin *h*. If a left hand rotation of the pipe is desired, that is a counter-clockwise direction, the pin *h* is removed and placed in the hole *j*, passing through the slots *k*¹ in both the plates or cheeks *b*, *b*. A movement of the handle *a* in a counter-clockwise direction will then

cause the jaws *c* and *d* to close upon the pipe and bring the teeth *p*, *p*, *p* in gripping contact with the wall thereof causing a rotation in the counter-clockwise direction, and as 5 the resistance to rotation offered by the pipe increases, the pressure of the jaws thereon increases by reason of the leverage exerted through the short leverage or distance from bolt *e* to pin *h* in hole *j*, said increase in 10 pressure on jaw *d* being caused by the tendency of the pin *h* to slide upon the inclined walls of the slots *k* with relation to the center line of the handle *a*.

It will be observed that the pin *h* which 15 connects the handle and adjacent end of one of the jaws serves as a fulcrum pin for drawing the jaws together and that it has its bearing against one end of the slot in which it lies, or otherwise stated against 20 the web or neck between the slots, on one side or the other thereof, according as the device is moved in one direction or the other in its clamping operation.

The device permits of a rotation of the 25 pipe or casing in either direction without removing the wrench therefrom and in that respect possesses advantages over the present forms of wrench, which necessitates a removal from the pipe and reversal of position 30 in order that the gripping may take place for rotating in the opposite direction.

When the wrench is removed from the pipe or casing the swinging of the jaw *c* out of position with respect to the handle *a* 35 is limited by the stops *l* and *o* on the jaw *c* coming in contact with either the stops *m* on the handle *a* or the stop piece *n* on the plates or cheeks *b*, or both.

It is intended that this wrench shall be 40 provided with a number of jaws *c* and *d* of different capacities similar in design to those shown in Figs. 1 and 2 so that the wrench may be used on pipe of different diameters, the substitution of jaws being readily accomplished 45 by removing the bolt *e* and inserting the jaws of larger capacity in the place occupied by the removed jaws.

We prefer to use the individual slots *k* and *k'* as shown in Fig. 1 in the side plates 50 or cheeks *b*, instead of making one continuous slot as hereinbefore mentioned although

the invention in its broadest sense embodies both forms.

Having thus fully described our invention what we claim as new and desire to 55 secure by Letters Patent, is:—

1. In a wrench, an operating handle, and a pair of jaws hinged together and one of them pivotally connected to the handle, and a shiftable fulcrum for connecting the handle 60 and adjacent end of one jaw, said fulcrum comprising a pin interchangeable from one to another of a plurality of openings formed on the fulcrum side of the wrench, to adapt the wrench to turn an object to the right or 65 to the left according to the adjustment of the fulcrum pin.

2. In a wrench, an operating handle and a pair of jaws hinged together and one of them pivotally connected to the handle, and a 70 shiftable fulcrum for connecting the handle and adjacent end of the other jaw, said fulcrum comprising a pin interchangeable from one to another of a plurality of registering 75 openings formed respectively in the handle and the adjacent end of one of the jaws, one set of the openings being elongated and forming a fulcrum bearing for the pin, to adapt the wrench to turn an object to the right or to the left according to the adjustment 80 of the fulcrum pin.

3. In a wrench, an operating handle and a pair of jaws hinged together and one of them pivotally connected to the handle, a shiftable fulcrum for connecting the handle 85 and adjacent end of one jaw, said fulcrum comprising a pin interchangeable from one to another of a plurality of openings formed on the fulcrum side of the wrench, to adapt the wrench to turn an object to the right 90 or to the left according to the adjustment of the fulcrum pin, and coacting stops formed respectively on the handle and one of the jaws to limit the movement of the handle and jaws in respect to each other. 95

In testimony whereof, we affix our signatures in presence of two witnesses.

EUGENE KIBELE.

WALTER G. VREELAND.
